UNITED STATES PATENT OFFICE.

LIZZIE TALLEY GULICK, OF CORSICANA, TEXAS.

BLIND-STOP.

SPECIFICATION forming part of Letters Patent No. 357,381, dated February 8, 1887.

Application filed November 30, 1886. Serial No. 220,274. (No model.)

To all whom it may concern:

Be it known that I, LIZZIE TALLEY GULICK, of Corsicana, in the county of Navarro and State of Texas, have invented a new and Improved 5 Blind-Clamp, of which the following is a full, clear, and exact description.

This invention relates to window-blind clamps; and it consists, essentially, of an attachment whereby the blind may be securely 10 held to such position as may be required, all as will be hereinafter more fully described, and specifically pointed out in the claims.

Reference is to be had to the accompanying drawings, forming a part of this specification, 15 in which similar figures of reference indicate corresponding parts in both the views.

Figure 1 is a face view of a portion of a blind, representing the same as provided with my improved form of clamp, the clamp being 20 shown in section on the broken line xx of Fig. 2; and Fig. 2 is a view taken on line yy of Fig. 1.

In the drawings above referred to, 10 represents the slats of an ordinary form of blind. 25 11 is the slat-bar, and 12 the lower cross-bar of the blind-frame.

My attachment consists, essentially, of a metallic plate bent at right angles to form flanges 2 and 3, the flange 2 being provided with apertures 4, while the flange 3 is finely corrugated. 30 Across the face of the flange 3 there is secured a spring-retaining strip, 5, which bears closely against the face of the corrugated flange, which strip carries a set-screw, 6.

35 The device just described is secured to the lower cross-bar, 12, by means of screws or nails that are passed through the apertures 4 in a position so that the flange 3 will project outward at right angles from the face of the cross-bar 40 in a line just below one side of the slat-bar 11.

To this slat-bar 11 there is secured a corrugated strip, 7, upon the upper end of which there is formed a socket, 8, within which the slat-bar fits, and the bar 7 is passed between 45 the flange 3 and the strip 5, the corrugated

face of the strip 7 resting against the corrugated flange 3, and being held thereto by the action of the spring-retaining strip.

With such a clamp as I have described the slats 10 may be held in such position as may 50 be required, for although, when subjected to any positive pull, the strip 7 will slip upon the face of the flange 3, said strip will be held to said flange by the action of the retaining-strip 5, which acts as a spring to hold the 55 strip 7 and the flange 3 together with sufficient force to resist the action of the wind.

If it is desired to lock the slats in the position in which they are shown in the drawings, the set-screw 6 is advanced so that it will bear 60 against the face of the strip 7 and hold the parts against any possible movement, thus preventing the slats from being turned from the outside.

Having thus fully described my invention, 65 I claim as new and desire to secure by Letters Patent—

1. A blind-clamp consisting of a corrugated flange or plate, a spring-retaining strip arranged in connection therewith, a corrugated 70 strip arranged to fit between the spring-strip and the corrugated flange, a means for connecting the corrugated plate to the blind-frame, and a means for connecting the corrugated strip to the slat-bar, substantially as de- 75 scribed.

2. The combination, with a window-blind, of a corrugated flange or plate connected with the frame thereof, a spring-retaining strip, 5, a corrugated bar arranged between the retaining-strip and the corrugated flange, a socket formed upon the corrugated bar and adapted to receive the slat-bar, and a set-screw carried by the retaining-strip, substantially as described. 80
